UNITED STATES PATENT OFFICE.

HARRY L. ANSTEY, OF OYSTER BAY, NEW YORK.

INTERNAL-COMBUSTION ENGINE.

1,124,581.

Specification of Letters Patent. Patented Jan. 12, 1915.

Application filed March 31, 1913. Serial No. 757,922.

To all whom it may concern:

Be it known that I, HARRY L. ANSTEY, a citizen of the United States, and a resident of the town of Oyster Bay, county of Nassau, and State of New York, have invented certain new and useful Improvements in Internal-Combustion Engines, of which the following is a specification.

The purpose of my invention is to so construct and correlate the parts as that the explosive mixture may be introduced into the cylinder or cylinders of the engine, as the case may be, and the exhaust or products of combustion expelled therefrom by the use of controllers or valves of a new form, so constructed and arranged that simplification, noiselessness and reliability of the structure are effected and other important advantages secured.

My invention is adapted to use in conjunction with each separate cylinder in the engine, however many they may be, but the advantages are more compactly secured if the cylinders be arranged in pairs with my improved controller or valve mechanism located between them. I will in the first instance, therefore, in the drawings and description hereof illustrate and describe the construction as applied to a pair of cylinders, and later on in the specification refer to the use in conjunction with an individual or single cylinder.

Generally stated the invention consists in a suitably constructed flat disk arranged to continuously revolve within a suitable casing located between the two cylinders composing the pair of cylinders referred to. The disk has holes or gas ports made through it adapted to connect with intake and exhaust ports in the casing within which it revolves and which connect at appropriate places with the two cylinders in such manner that one cylinder will have its intake and also its exhaust sufficiently before its companion or adjoining cylinder to effect the proper timing and operation of the engine as a whole. The disk is given continuous rotation always in the same direction by suitable driving mechanism connected with the main shaft of the motor.

It will be understood that my improved engine will be provided with the usual accessories or appurtenances of such apparatus, having in view, as is well known, the

power and character of the engine and the work it is to perform, such as ball bearings, suitable oiling appliances, provision for water or air cooling and the like. I do not illustrate or describe many of these appliances because their various forms and arrangements are now well known to those who are skilled in this art and their presence would merely complicate and confuse the drawings.

In the drawings, Figure 1 is a vertical sectional view on the line A—B of Fig. 2, looking to the right in the direction of the arrows; Fig. 2 is a vertical sectional view through the center line of the cylinders on the line C—D, looking to the left in the direction of the arrows; Fig. 3 is a plan view; Figs. 4, 5, 6 and 7 are diagrammatic views of the revolving disk and gearing which actuates it, taken on the section C—D of Fig. 2 and looking to the left in the direction of the arrows and showing the valve disk in four different positions; Fig. 8 is a diagrammatic view showing the position of the ports in the disk and in the disk casing corresponding to that shown in Fig. 4 and 80 illustrating the parts as applied to two cylinders; Fig. 9 is a like view corresponding to Fig. 5; Fig. 10 is a like view corresponding to Fig. 6; Fig. 11 is a like view corresponding to Fig. 7.

1 represents the base of the machine which may be made of such construction and form as preferred. 2 represents the crank case. 3 the main shaft. 4 cranks on the shaft. 5 the balance wheel. 6, 6. the piston rods. 7, 7. the pistons. 8, 8. the cylinders. 9 water jacket on the cylinders. 10 a countershaft. 11 a gear on the main shaft which meshes into a similar gear 12 on the countershaft. 13 a pinion on the countershaft 90 which meshes into a spur gear 14 on the edge of the disk 15 which is, through the described gearing, continuously driven in one direction from the main shaft. In the example shown the disk is located between the two cylinders. It revolves on a hub 16 and is surrounded at its upper part by a casing 17.

The explosive mixture is supplied to the cylinders as follows: The disk (see Figs. 4 to 7) is supplied with a series of ports 18. Four are shown in the present example. They are equally spaced and are mere open

ings or holes extending from side to side through the disk and in the walls of the casing there are other ports 19 and 19^a which are so spaced as to permit respectively the intake of the explosive mixture and the expulsion of the exhaust at the appropriate time, depending upon the special construction of the engine, as will be hereinafter described. The fuel supply and exhaust pipes connect with these openings or ports 19 in the casing as shown. The explosive mixture is conducted to the cylinders through conduits or ducts as follows (see Figs. 1, 2 and 3). 20 is the supply pipe for the explosive mixture, which of course connects at one end with the carburetor. Near the cylinders it branches to right and left as shown in Fig. 3. One branch 21 connects with the appropriate port 19 in the casing 22, as shown, and discharges through one of the ports in the disk 15, when it properly registers with the said opening in the casing, thence through the opposite walls of the casing and thence being conducted by a conduit 23 discharges into the left hand cylinder, all as shown in Fig. 3. The other branch 24 of the fuel supply pipe similarly connecting with appropriately located and registering openings or ports in the disk casing and disk and conduit 25, discharges at 26 into the right hand cylinder. The exhaust ports are similarly arranged, that is to say: 27 is the main exhaust pipe which likewise has two branches, one 28 (see Fig. 3) after connecting with suitable openings or ports in the disk casing and disk, connects at 29 with the left hand cylinder and the branch 30 similarly connects by a passage 31 with the right hand cylinder. 32^a is a water supply pipe and 32 and 33 are water outlet pipes for the cooling system. 34 and 35 are spark plugs.

The operation of the apparatus is illustrated diagrammatically in Figs. 4 to 11. Figs. 4, 5, 6 and 7 illustrate the revolving disk and co-acting parts and the manner in which the equally spaced ports 18 in it are made to intermittently register with the intake port 19 and the exhaust port 19^a in the disk casing, which are, as above stated, suitably connected with the cylinders. In Figs. 4 to 7, both inclusive, for simplification in explanation, the parts are shown as applicable to a single cylinder. In Figs. 8, 9, 10 and 11, the disk is represented as projected in a straight line and the appropriate intake and exhaust openings through the casing connecting with the cylinders are also shown and especial attention is called to the fact that in these last named figures (8 to 11 both inclusive) the parts are illustrated as applied to a pair of cylinders.

Referring now to Figs. 4 to 7, and bearing in mind that the port 19 represents the intake opening through the casing, which con-

ncts with one of the cylinders and that the port 19^a represents the exhaust port from the same cylinder, it will be noted, by reference to Fig. 4, that the two uppermost ports 18 which are mere openings or holes made 70 directly through the revolving disk, are so disposed that (the disk revolving in the direction of the arrow) the right hand upper port has just ceased registration with the exhaust port 19^a in the casing and that the piston 7 of that cylinder is at its uppermost position, the products of combustion having all been exhausted from that cylinder. In Fig. 5 it will be noted that the crank shaft has made a half revolution and consequently 80 that the piston 7 is at its lowermost position and that during this movement of the parts, the disk 15 being in continuous revolution, that the right hand upper port 18 in the disk has passed away from the exhaust port 19^a 85 and that the upper left hand port 17 has made a transit completely across the intake port 19 in the casing, during which movement of the parts, the descending piston 7 has drawn in to the cylinder a fresh charge 90 of explosive mixture.

Referring now to Fig. 6, it will be seen that the crank shaft has made a complete revolution and that the piston is again at its uppermost position, during which it has effected compression of the charge and that during this operation there was no escape of the charge from the cylinder possible because both of the upper ports 18 in the disk have during the upward movement of the 100 piston, been entirely out of registration with either of the ports 19 and 19^a in the casing. Upon the completion of the compression of the charge, that is to say, when the piston commences its second downward movement, 105 the charge is fired, and in Fig. 7 the piston is seen again at its lowest position. Now in order that the exhaust of the products of combustion from the cylinder may be again effected, it will be observed that the port 18 110 in the disk 15 which had previously been the intake port, is now just commencing to register with the exhaust port 19^a, so that it now becomes the exhaust port, and furthermore that the port 18 which is now farthest to the 115 left, as shown in Fig. 7 and which formerly was an inactive port, it then being in the lower portions of the disk, has now moved inwardly, so that upon the return or exhaust movement of the piston 8, it will approach nearer and nearer to the port 19, so that by the time the exhaust has been effected, it will suitably register therewith and become the intake port, as shown in Figs. 4 and 5. In this way, by the continuous rotation of the disk 15, the equally spaced ports 18 in it are caused successively to come in registration first with the intake ports in the casing and then by continued rotation of the disk, successively become the 120

exhaust ports. It will further be particularly noted that whereas the ports 18 in the disk at the commencement of the downward and upward movements of the piston 7, are 5 not in full registration with the ports 19 and 19^a as the case may be, nevertheless that their registration therewith is such as to exactly coincide with the position and speed of movement of the piston, in other words, that 10 the degree of the opening, either for the intake or for the exhaust, is co-extensive and contemporaneous with the requirements which are determined by the location and speed of movement of the piston and in 15 order that a "lead," as it is called, may be given to the intake or the exhaust operations, one or both, I suitably change the relative size and shape of the ports in the sides of the casing, or suitably change the timing 20 of the disk relative to the position of the crank shaft.

Referring to Figs. 8 to 11, it will be noticed that the movement of the parts and the results secured are the same as above 25 described and that they have been illustrated as applied to a pair of cylinders, that is to say, the heavy black line indicates the disk 15, the two open spaces 18 therein represent two of the ports in the disk and the 30 two right hand openings by the sides of the disk represent the intake openings in the casing and the two left hand openings represent the exhaust openings in the casing, in other words, the opening 36 represents the 35 connection with one of the cylinders, the opening 37 on the opposite side of the disk connects with the carburetor, the next pair of openings to the left are 38 connecting with the carburetor, and 39 with the opposite cylinder, the next two openings to the left are 40, the exhaust from one of the cylinders, and 41 the connection with the muffler, the next pair of openings to the left are 42 connecting with the opposite cylinder 45 and 43 connecting with the muffler.

The operation is obvious. Fig. 8 coincides with Fig. 4. The openings in the disk are the same as the upper left hand opening in Fig. 4 and it will be seen that the right 50 hand opening 18 is just about to come into registration with the passageways 36 and 37 which connect with the carburetor at one side and one of the cylinders at the other and likewise, still referring to Fig. 8, that the left hand opening 18 has just passed away from registration with the passageways 40 and 41 which permit the exhaust to 55 pass from the cylinder to the muffler, as likewise shown in Fig. 4, also that in Fig. 9 the right hand port 18 in the disk is just about to make registration with the intake ports 38 and 39 which permit the intake of a fresh charge from the carburetor to the second cylinder and that the left hand opening 18 has just passed away from the ports 60 65

42 and 43 which permitted the exhaust to pass from the second cylinder, so that this Fig. 9 coincides with Fig. 5.

Without further elaborate description it will be found that Figs. 10 and 11 similarly 70 coincide with Figs. 6 and 7, being made applicable, however, to a pair of cylinders instead of a single one.

Although I have shown the ports in the disk and in the casing as being substantially rectangular, they may be of such other form as preferred. Indeed in some constructions of engine, it will be desirable to make them of different form in order to save space or secure volume of intake or 80 discharge. Therefore the contour of these openings or ports is immaterial.

The number and spacing of the ports in the disk and in the walls of the casing will of course vary depending upon the number 85 of cylinders co-acting with a single disk and also the speed at which the disk is driven. These matters will in each case be determined by the designer of the engine. No arbitrary rule controls in the matter. The 90 relative dimensions of the parts may also be such as preferred. There is no arbitrary size relation that controls. All that is essential is that the dimensions shall be such as will produce the stated result, that is to 95 say, such as will admit of the preferred or suitable opening of an exhaust port during the appropriate upward movement of the piston after an explosion and the like closing of the exhaust and opening of the intake 100 during the next downward or intake movement of the piston, and the closing of both the exhaust and the intake ports during substantially the whole of the second or compression upward movement of the piston 105 continuing during the second downward or power stroke of the piston.

It will be obvious to those who are familiar with this art that modifications may be made in the details of construction and yet 110 the essentials of the invention be embodied. I therefore do not limit myself to the details described or illustrated.

I claim:

1. An internal combustion engine having 115 a stationary cylinder, a disk and disk casing by the side of the cylinder, ports in the cylinder and in the disk casing, a plurality of ports in the disk, said ports co-actively operating to adjust and control the intake 120 of the fuel and the ejection of the products of combustion, and means to move the disk, for the purposes set forth.

2. An internal combustion engine having 125 a stationary cylinder, a disk and disk casing by the side of the cylinder, ports in the cylinder and in the disk casing, a plurality of ports in the disk, said ports co-actively operating to adjust and control the intake of 130 the fuel and the ejection of the products of

combustion, a reciprocating piston within the cylinder connected to a crank shaft, and means actuated by the crank shaft for revolving the disk always in one direction, for the purposes set forth.

3. An internal combustion engine having a stationary cylinder, a disk and disk casing by the side of the cylinder, a plurality of ports in the disk, other ports in the cylinder and in the disk casing, said ports co-actively operating to adjust and control the intake of the fuel and the ejection of the products of combustion, the ports in the disk being equally spaced, but those in the disk casing so spaced that the ports in the disk which connect with them may be simultaneously closed by that part of the wall of the casing which is between the edges of the ports in it, and means to revolve the disk always in the same direction, for the purposes set forth.

4. An internal combustion engine having a stationary cylinder, a disk and disk casing by the side of the cylinder, ports in the cylinder and in the disk casing, a plurality of ports in the disk, said ports co-acting together to adjust and control the intake of the fuel and the ejection of the products of combustion, a gear on the periphery of the disk, a pinion intermeshing therewith driven from the crank shaft whereby the disk is always revolved in the same direction, the complete revolutions of the disk being less frequent than the complete revolutions of the crank shaft, for the purpose set forth.

5. An internal combustion engine having a stationary cylinder, a disk and disk casing by the side of the cylinder, ports in the cylinder and in the disk casing, a plurality of ports in the disk, a gear on the periphery of disk, gearing connecting the crank shaft with the gear on the disk, said gearing being so related that the disk revolves slower than the crank shaft, for the purposes set forth.

6. An internal combustion engine having a pair of stationary cylinders, a disk and disk casing located between the cylinders, ports in the opposite sides of the disk casing connecting with the respective cylinders, other ports in the disk which are not coincident with those in the sides of the casing, said ports co-actively operating to adjust and control the intake of the fuel and the ejection of the products of combustion, and means to revolve the disk always in the same direction, for the purposes set forth.

7. An internal combustion engine having a pair of stationary cylinders, a disk and disk casing located between the cylinders, ports in the disk which are equally spaced, other ports in the disk casing which connect respectively with the cylinders and which are so spaced that all of the ports in the disk may be simultaneously closed by that part

of the walls of the casing which is between the edges of the ports in them, said ports co-actively operating to adjust and control the intake of the fuel and the ejection of the products of combustion, and means to revolve the disk always in the same direction simultaneously with, but to a less degree than the revolution of the crank shaft, for the purposes set forth.

8. A device for regulating the intake and exhaust in internal combustion engines, comprising a flat disk provided with a plurality of equally spaced ports, a disk casing provided with ports adapted to register with those in the disk, passageways for the fuel, other passageways for the exhaust, both connecting with the appropriate ports in the casing, and means to continuously revolve the disk always in the same direction.

9. A device for regulating the intake and exhaust in internal combustion engines comprising a flat disk provided with a plurality of equally spaced ports, a disk casing provided with ports adapted to register with those in the disk, passageways for the fuel, other passageways for the exhaust, both connecting with the appropriate ports in the casing, a gear on the periphery of the disk, a countershaft parallel with the crank shaft and driven from it, a pinion on the countershaft that meshes into the gear on the disk, whereby the disk will be continuously revolved always in the same direction, and a water jacket inclosing the part of the casing within which the ports are located.

10. A device for regulating the intake and exhaust in internal combustion engines, comprising a flat disk provided with equally spaced ports, a disk casing provided with ports adapted to register with those in the disk, said casing and disk being located between two adjoining cylinders, passageways for fuel, other passageways for the exhaust connecting both cylinders with the appropriate ports in the casing, and means to continuously revolve the disk always in the same direction.

11. An internal combustion engine having a stationary cylinder, a disk, a disk casing by the side of the cylinder, ports in the cylinder and in the disk casing, a plurality of ports in the disk, said ports co-actively operating to adjust and control the intake of the fuel and the ejection of the products of combustion, the disk projecting downwardly into the splash chamber of the crank chamber, and means to revolve the disk for the purposes set forth.

12. A device for regulating the intake and exhaust in internal combustion engines comprising a flat disk provided with a plurality of equally spaced ports, a disk casing provided with ports adapted to register with those in the disk, passageways for the fuel, other passageways for the exhaust, both con-

necting with the proper ports in the casing, a gear on the periphery of the disk, a countershaft parallel with the crankshaft and driven from it, a pinion on the countershaft 5 that meshes into the rear on the disk, whereby the pinion and the lower arc of the disk will be within the splash chamber of the crankshaft and a water jacket inclosing the part of the casing within which the ports are 10 located.

13. A device for regulating the intake and exhaust in internal combustion engines comprising a flat disk provided with a plurality of equally spaced ports, a disk casing provided with ports adapted to register with 15 those in the disk, passageways for the fuel,

other passageways for the exhaust, both adapted to register with the appropriate ports in the casing, a gear on the periphery of the disk, means driven from the crankshaft whereby the disk may be revolved always in the same direction, said means and the lower arc of the disk being within the splash chamber of the crankshaft. 20

In testimony whereof I have signed my 25 name to this specification in the presence of two subscribing witnesses.

HARRY L. ANSTEY.
